UNITED STATES PATENT OFFICE.

JOSEPH PAXTON LOWE, OF SOUTH SEATTLE, WASHINGTON.

SWITCH-OPERATING MECHANISM.

SPECIFICATION forming part of Letters Patent No. 781,835, dated February 7, 1905.

Application filed May 4, 1904. Serial No. 206,385.

To all whom it may concern:

Be it known that I, JOSEPH PAXTON LOWE, a citizen of the United States, residing at South Seattle, in the county of King and State of Washington, have invented a new and useful 5 Switch-Operating Mechanism, of which the following is a specification.

This invention relates to switch-operating devices of that class which are connected with 10 cars and adapted to be operated either from the platform or from the inside of the car to which it is attached for the purpose of setting the switch in advance of the car without necessarily stopping the latter.

15 The invention has for its object to provide a device of this class which shall be adapted to set or throw a switch either at the right or the left hand side of the track and which shall, moreover, be capable of being adjusted to various 20 positions, so as to operate the switch of a siding turning either to the right or to the left from the main line, as the case may be.

With these and other ends in view, which 25 will readily appear as the nature of the invention becomes better understood, the same consists in the improved construction and novel arrangement and combination of parts, which will be hereinafter fully described, and particularly pointed out in the claims.

30 In the accompanying drawings has been illustrated a simple and preferred form of embodiment of the invention, it being understood, however, that no limitation is necessarily made to the precise structural details therein exhibited, but that the right is reserved to any 35 changes, alterations, and modifications which may be resorted to within the scope of the invention and without departing from the spirit or sacrificing any of the advantages of the 40 same.

In said drawings, Figure 1 is a perspective front view of the improved switch-operating device attached to a car, portions of the latter having been broken away for the purpose of 45 more clearly showing the parts of the invention. Fig. 2 is a top plan view. Fig. 3 is a vertical sectional view taken on the line 3 3 in Fig. 2. Fig. 4 is a vertical sectional view taken on the line 4 4 in Fig. 2. Fig. 5 is a 50 vertical transverse sectional view taken on the line 5 5 in Fig. 4. Fig. 6 is a perspective de-

tail view, enlarged, showing one of the switch-operating members and the operating mechanism connected with the same. Fig. 7 is a perspective detail view of the pivoted head-block for actuating the switch - operating members.

Corresponding parts in the several figures are indicated by similar numerals of reference.

60 My improved switch-operating device includes a bed-plate or base-plate 1, which is firmly secured in a suitable position to the body 2 of the car and which is provided with a plurality of forwardly-projecting studs 3 65 3, having shoulders or offsets 4. The studs 3 serve to support a frame-plate 5, which is provided with slots 6 6, alining with the studs 3 3 and engaging the shoulders or offsets 4 of the latter so as to be supported at 70 a suitable distance from the base-plate in such a manner as to be capable of sliding laterally upon the reduced ends of the latter. The frame-plate 5 is connected with the studs of the base-plate by means of cotter-pins or 75 keys 7 passing through the reduced front ends of the latter. The frame-plate 5 is provided with a plurality of posts 8 for the support of a face-plate 9, having perforations 10 for the passage of stud-bolts 11, engaging screw- 80 threaded recesses in the posts 8, thereby securing the face-plate firmly to the frame-plate 5 and cooperating therewith to constitute a frame which is laterally slidable upon the studs of the base-plate.

85 The face-plate, the frame-plate, and the base-plate are each provided with perforations 12, which are in alinement with each other and which afford bearings for a shaft 13, extending rearwardly under the floor of 90 the car or car-platform, as the case may be. In the drawings the device has been shown as applied to a car-platform, which is provided with a transverse slot 14 for the passage of an operating - lever 15, which extends upwardly from the rear end of the shaft 13. The latter has an additional bearing in a stirrup 16, which is connected with the lower edge of the face-plate, and upon said shaft, between the stirrup and the face-plate, is 95 mounted a rocking head 17, which is composed of a rear member 18 and a front mem-

ber 19, which are connected and spaced apart by means of a pair of bolts 20 and 21, carrying antifriction-rollers 22.

The face-plate is provided adjacent to the 5 sides of the rocking head 18 with forwardly-extending pins 23 and 24, upon which are fulcrumed a pair of levers 25 and 26, the outer ends of which are supported upon the ends of a leaf-spring 27, which is suitably supported 10 upon and connected with the stirrup 16. The inner ends of the levers 25 and 26 extend over and are normally supported upon the friction-rollers upon the bolts 20 and 21.

Suitably connected with the upper part of 15 the face-plate 9 are a pair of laterally-extending brackets 28, carrying vertically-disposed sleeves 29. Similar sleeves 30 are supported in perpendicular alinement with the sleeves 29 by means of brackets 31, extending 20 laterally from the lower part of the face-plate. The latter brackets are made of resilient material, such as spring-steel, in order that the sleeves and the members supported 25 therein may be capable of yielding slightly for the purpose to be hereinafter described. Loosely supported in the sleeves 29 30 at either side of the face-plate are vertically-disposed rods 32 and 33, provided at their outer ends with flattened sharp-edged members, 30 which I designate the "spades" 34 and 35, which are adapted to enter between the rails and the switches for the purpose of moving the latter to the desired position by a simple quarter-turn of the spade-carrying member. The 35 spade-carrying rods or members 32 and 33 are extended through slots 36 near the outer ends of the levers 25 and 26 and are provided above said levers with collars 37, fixed thereon by means of set-screws 38 or equivalent means, 40 whereby they may be set and adjusted to various positions, said collars being provided with laterally-extending arms, designated, respectively, 39 and 40, and provided with vertical slots 41 and 42. At a suitable distance 45 below the levers the rods 32 and 33 are provided with washers 43, supported upon transverse keys or pins 44, to prevent the displacement in an upward direction of said spade-carrying rods or members.

50 Pivottally connected with the front member 19 of the rocking head 17 are a pair of laterally-extending arms or levers 45 and 46, each of which is bifurcated or forked at its outer end, the members of the forks being provided 55 with vertical slots 47 and 48. The slotted arms 39 and 40, connected with the spade-carrying members 32 and 33, are disposed between the upper ends of the bifurcated outer ends of the links 45 and 46, and connecting 60 pins or bolts 49 and 50 are extended through the slots 41 49 and 42 50, respectively, thus forming loose connections between the links 45 and 46 and arms 39 and 40, respectively.

51 designates a rod connected securely with 65 the rear side of the face-plate 9 and also with

the frame-plate 5, through which latter it extends rearwardly through a slot 52 in the base-plate. The rear end of the rod 51 is pivotally connected with the lower end of a lever 53, which is fulcrumed to any suitable fixed 70 point, in the present instance upon the apron of the car-platform. The upper end of the lever is provided with a button or operating-handle 54 and it is capable of being adjusted at either side of a central stop 55 and practically in contact with either one of two end stops 56 and 57, whereby the upper end of the operating-lever, which in the present instance may be described as being made of resilient material, may be retained in adjusted 80 position, thus securing in adjusted position the frame comprising the plates 5 and 9 and related parts, which by means of the said lever may be moved laterally within the limits of the length of the slots 6, working upon 85 studs 3 and supporting the slideable frame carrying the operating mechanism in proper position upon the base-plate.

The parts of the device are to be so disposed and adjusted that when the carrying-frame, including the plates 5 and 9 and related parts, is at one end of its movement the switch of a siding turning to the right from the main line shall be capable of being operated by the switch-operating members. When the 90 carrying-frame is at the opposite limit of its movement, the switch-operating members will be adapted to operate the switch of a siding turning to the left from the main line. It will be seen that provision is made for operating a switch either at the right or the left side of the track; but only one switch is actually operated at any one time, as will be readily understood.

To operate this device, the carrying-frame 105 is adjusted, by means of the lever 23, so as to be capable of operating a switch upon the next siding or at the next divergent track to be encountered. When the switch is approached, the car is slowed down, and when the switch-operating rod 32 or 33, as the case may be, is directly over the point of the switch-tongue the lever 15 is manipulated to rock the head 17 in the proper direction, thus causing one of the roller-carrying pins 20 or 21 to bear against 110 the under side of one of the levers 25 or 26, depressing the outer end of such lever until by bearing against the washer 43 the switch-operating member will be depressed against the tension of the leaf-spring 27 between the 115 switch-tongue and the adjacent rail. Should the switch-tongue have become slightly displaced, the resiliency of the lower bracket 31 will permit the spade 34 or 35 to yield slightly and to enter properly between the switch-tongue and the adjacent rail. At the same time the link 45 or 46, connected with the slotted arm extending from the switch-carrying member which is being operated, will, being drawn in an inward direction by the tilt- 120

130

ing action of the head 17, with which it is connected, impart to said switch-operating member a quarter-turn, causing the switch-tongue to be instantly set to the proper position, when the car, properly guided, may proceed upon its way.

As will be seen from the foregoing description, this device is simple in construction and may be easily applied to cars of ordinary construction without material alterations of any kind. By this device switches of any kind and located in any ordinary manner may be set or operated without stopping the car and without the necessity of the conductor or motorman leaving his post. The switch-operating members, as will be observed, move in a straight vertical direction and will unfailingly enter between the switch-tongues and the rails and actuate the former in the manner described.

Having thus described the invention, what is claimed is—

1. A frame, a rocking head connected pivotally therewith, vertically-adjustable and partially-rotatable switch-operating members supported by the frame, and levers fulcrumed upon the frame and connected with the rocking head and with the switch-operating members which are thereby actuated.

2. A frame, sleeve-supporting brackets extending laterally from the upper part of said frame, resilient sleeve-supporting brackets extending laterally from the lower part of said frame, and switch-operating members journaled in the sleeves.

3. A frame having laterally-extending sleeve-supporting members, switch-operating members mounted rotatably in the sleeves and provided at their lower ends with switch-operating devices, and means for simultaneously depressing and partly rotating the sleeve-operating members.

4. A frame, vertically-movable and partly-rotatable switch-operating members connected with said frame, collars connected adjustably with said members and having laterally-extending slotted arms, a rocking head connected with the frame, links connected with said rocking head and having slotted prongs connected loosely with the slotted arms extending from the switch-operating members, levers connected pivotally with the frame, supported at their inner ends upon antifriction members connected with the rocking head and provided at their outer ends with slots including the switch-operating members, and washers supported upon the latter below the outer ends of the levers.

5. A base-plate having studs, a frame having slots slidably engaging said studs and supported upon the latter, switch-operating members carried by said frame, a rod connected with the latter, extending rearwardly from the same, a lever fulcrumed to a fixed point and connected with said rod, and means for

adjusting said lever and for retaining it in adjusted position to secure the frame carrying the switch-operating mechanism at either limit of its movement.

6. A frame carrying switch-operating mechanism including vertically-movable and partly-rotatable switch-operating members, levers connected with said frame, supporting and adapted to effect the vertical movement of said levers, and a leaf-spring supporting said levers.

7. A frame, a rocking head connected with said frame, a stirrup depending from the latter, vertically-movable and partly-rotatable switch-operating members supported by the frame, levers fulcrumed upon the frame and having slots including the switch-operating members, suitably-supported washers upon the latter, antifriction members connected with the rocking head and supporting the inner ends of said levers, a leaf-spring supported by the stirrup and supporting the outer ends of said levers, and means connected with the rocking head for effecting partial rotation of the switch-operating members.

8. A frame, vertically-movable and partly-rotatable switch-operating members supported by said frame, levers fulcrumed upon the frame and having slots including the switch-operating members, collars adjustable upon the latter above the levers and having laterally-extending arms, washers supported upon the switch-operating members below the levers, a stirrup depending from the frame, a shaft journaled in said stirrup and in the frame and having an operating-lever at its rear end, a rocking head mounted upon said shaft adjacent to the frame, antifriction members connected with said rocking head and supporting the inner ends of the levers engaging the switch-operating members, a leaf-spring supported by the stirrup and supporting the outer ends of said levers, and link connections between the arms extending from the collars upon the switch-operating members and the corners of the rocking head.

9. A base-plate, a laterally-movable frame supported by said base-plate, vertically-movable and partly-rotatable switch-operating members carried by said frame and adapted to engage switches at the right and left hand side of the track, a shaft journaled in said frame and slidably through a slot in the base-plate, a hand-lever connected with said shaft, a rocking head mounted upon the latter, and means connected with said rocking head for actuating the switch-operating members.

In testimony that I claim the foregoing as my own I have hereto affixed my signature in the presence of two witnesses.

JOSEPH PAXTON LOWE.
